UNITED STATES PATENT OFFICE.

SAMUEL GOLDSTEIN, OF NEW YORK, N. Y.

SAD-IRON.

1,163,528.

Specification of Letters Patent.

Patented Dec. 7, 1915.

Application filed August 31, 1915. Serial No. 48,180.

To all whom it may concern:

Be it known that I, SAMUEL GOLDSTEIN, a citizen of the United States, and a resident of the city of New York, borough of Manhattan, in the county and State of New York, have invented a new and Improved Sad-Iron, of which the following is a full, clear, and exact description.

My invention relates to sad irons heated by the combustion of gas within the iron.

An object of my invention is to provide a simple, strong, efficient, and inexpensive iron, in which the flame is generated by a burner located within the iron, said flame playing against a perforated false bottom of the iron.

A further object of the invention is to provide a sad iron in which the products of combustion coming from the burner, are deflected from the operator's hand by providing a baffle on the cover of the iron.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a perspective view of my sad iron; Fig. 2 is a longitudinal vertical section; Fig. 3 is a transverse vertical section on the line 3—3 of Fig. 2; and Fig. 4 is a horizontal section on the line 4—4 of Fig. 2.

Referring to the drawings, the main body 5 of the iron is in the shape of a hollow casing, which has a false bottom 6, having a longitudinal central slot 7 extending from the rear to the front of the casing. The slot 7 is walled longitudinally by partitions 8, extending from the false bottom 6 to the bottom 9 of the iron, whereby an air trough or channel is formed, which channel is open at the rear of the iron. The partitions 8 separate the space between the two bottoms of the iron into two chambers 10, which unite at the front, for the partitions 8 do not extend fully to the front of the iron. Each chamber 10 is open at the rear and also has an opening 11 at the front.

The false bottom 6 has perforations 12, which establish communication between the chambers 10 and the interior of the iron where a burner 13 is located above and in

alinement with the slot 7. The flame-generating outlets 14 of the burner are directed toward the false bottom 6, so that the flames will play thereupon.

To prevent the heat escaping through the side openings 15 of the casing from flowing on to the hand of the operator, the cover 16 of the iron is provided with a baffle plate 17, which is concavo-convex, the convex surface thereof having lugs 18 for engaging lugs 19 provided therefor in the cover 16, which prevent the turning of the baffle plate on the screw 20 which fastens the baffle plate to the cover. The screw 20 serves also as means for securing the handle 21 of the iron in place. The handle is prevented from turning on the plate by the lugs 18' engaging the handle. The body 5 is provided with a clamping member 22 for engaging the cover 16 and alining the same to the body, as is common in this class of irons.

While I have described the principle of operation, together with the device which I now consider to be the best embodiment thereof, I desire to have it understood that the device shown is merely illustrative and that such changes may be made as are within the scope of the appended claims.

I claim:

1. In a sad iron, a hollow casing; a perforated false bottom spaced from the bottom of casing; said casing having a central longitudinal air channel between the two bottoms open at the rear and extending through the length of the hollow of the casing; a burner located above said channel and adapted to direct the flame thereof against the perforated bottom; and a cover for said casing.

2. In a sad iron, a hollow casing having a bottom; a perforated bottom spaced from the first-mentioned bottom and having a central longitudinal slot; partitions from the perforated bottom to the bottom of the casing along the edges of the slot transforming the slot into an air channel open at the rear of the casing and at the front within the casing, said partitions dividing the space between the two bottoms into chambers, one to each side of the channel, communicating with each other and with the channel through the medium of the opening in the channel within the casing, said chambers being open in the rear of the casing and also in the front; a burner located above the air passage and adapted to direct the flame

thereof on to the perforated bottom; and a cover for said casing.

3. In a sad iron, a hollow casing, a burner therein, a cover for the casing, said casing having openings at the cover, a concavo-convex baffle plate having lugs on both faces thereof, said cover having lugs engaging the lugs on the convex surface of the baffle plate, a handle on the plate engaging the lugs on

the concave surface thereof, and a screw securing the handle and plate to the cover, said lugs on the cover and plate preventing the turning of the plate on the cover and of the handle on the plate. 10

SAMUEL GOLDSTEIN.
